UNITED STATES PATENT OFFICE.

HENRY E. HADDOCK, OF PHILADELPHIA, PENNSYLVANIA, ASSIGNOR TO
JOHN A. BRILL, OF PHILADELPHIA, PENNSYLVANIA.

CONVERTIBLE CAR.

SPECIFICATION forming part of Letters Patent No. 761,296, dated May 31, 1904.

Application filed August 21, 1903. Serial No. 170,240. (No model.)

To all whom it may concern:

Be it known that I, HENRY E. HADDOCK, a citizen of the United States, and a resident of the city and county of Philadelphia, State of Pennsylvania, have invented certain new and useful Improvements in Convertible Cars, of which the following is a specification.

The object of my invention is to make a car that can be readily converted from a so-called "closed" or "winter" car to a "summer" or "open" car. In order to accomplish this, the sides of the car are made up of a number of sashes and panels which can be easily slid or moved into such a position that they will occupy the least possible space and at the same time into a position that is not used for any other purpose, so that the panels will not be in the way of the occupants of the car nor in the way of those having charge of the car. This is accomplished without extending the height or in any way bulging any part of the car, so that the conventional shape of the car may be retained.

A further object of my invention is to provide a means whereby the sashes may be slid over each other to conserve space in storage and to expedite the movement into the storage space and also a locking and guiding means for locking the sashes in any position in which they may be placed.

Additional features and advantages will appear from the following description, in which reference is made to the accompanying drawings, forming a part hereof, in which—

Figures 1 and 2 are sectional views taken on the lines 1 1 and 2 2 looking in the direction of the arrows. Fig. 3 is a side elevation showing a part of the car with the panel and sashes removed and in place, certain details being omitted. Figs. 4 and 5 show the sashes. Fig. 6 shows the panel. Figs. 7 and 8 are sectional and perspective views of portions of a stanchion. Figs. 9 and 10 are sectional views taken on the lines 9 9 and 10 10 of Fig. 1 looking in the direction of the arrows. Fig. 11 is a section taken on the line 11 11 of Fig. 1 looking in the direction of the arrows. Fig. 12 shows the guide-frame. Figs. 13, 14, and 15 are an end elevation, a perspective view, and a side elevation, respectively, of a spring

for supporting the sashes. Figs. 16, 17, 18, and 19 are detailed views showing the sash-fasteners.

Throughout the various views similar reference characters designate similar parts.

The car is provided with the usual side sills 1, crossings 2, and flooring 3. From the sills extend the grooved stanchions 4, which support a roof 5 in the usual manner. The stanchions 4 are united by fixed panels 6, with the curtains 7 and curtain-rods 8 secured in the conventional way, and suitable curtain-grooves, 9 are formed in the stanchions 4. These stanchions are also provided with grooves 10 and 11 on each side for the sashes 12 and 13 and panels 14 and with metallic guiding-frames 15. The groove 11 is made so as to form a part of the lower portion of the groove 10 at one side thereof and deeper, as shown in Figs. 7 and 9. The upper portion of the groove 10 is deepened so as to permit the frame 15 to be sunk into the stanchion 4, so that the outer surface of the frame 15 is flush with the lower portion of the groove 10, and an edge of the frame 15, together with a wall 75 of the groove 10, forms a groove 16, which is a continuation of the groove 11, so that the panels 14 may slide freely over the frames 15. The upper ends of the stanchions 4 are enlarged to form horns 17, and the frames 15 are bifurcated at 18 to form two arms 19 and 20, the arms 19 being angular in cross-section and extending parallel to the panels 6 to form therewith grooves 21, which are continuations of the grooves 16, and the arms 20 form 85 guides for trunnions on the sashes, as will hereinafter appear. While the frame 15 may be made in one integral piece, it is found more convenient to divide it into several constituent parts, and so it is preferably made 90 of three pieces, which are divided on the line 22 a little above the crotch 18. The frames 15 are provided with grooves 23, which extend from their lower ends above the crotches 18 and lines 22 to projections 24, where one edge 95 is curved outwardly, then downwardly, and then upwardly to form a pocket 25, and then the groove 23 continues somewhat enlarged in the arms 20 in directions approximately parallel to the arms 19. The arms 20 termi- 100

nate near the ventilators of the roof, and at their upper ends and depending therefrom are diverging webs 26, with flanges 27, which extend far enough to support the sashes 12 as 5 appears below. Each end of the grooves 23 terminates in the frames 15, and these frames are secured in position by means of screws 28, which pass through perforations either in the groove 23 or in ears 29, made integral 10 with the arms 19 and 20. The frames 15 are also provided with perforations 30, which are adapted to receive bolts on the sashes. Immediately below the pocket 24 the stanchion 4 is cut away to form grooves 31, which are 15 deep enough to be flush with the outer surface of the frames 15 and extend far enough to hold the upper sashes 13.

The panels 14 each contain upper and lower bars 32 and 33, respectively, which are connected by outer and inner sheets of metal 34 and 35, the outer sheet 34 being fixed to both bars 32 and 33 by any suitable means, such as tacks or nails. The inner sheet 35 is fixed to the lower bar 33 and terminates at the upper 25 bar 32, where its end is overlapped by a metal strip 36, so that this end may have a relative movement between the strip and bar and yet not be disengaged from either. Slats 37 and 38 are secured to the sheets 34 and 35, respectively, to stiffen the panel without diminishing its capacity to slide in curved grooves. The panel is so made that the sheets 34 and 35 engage the walls of the grooves 10, and the sheet 35 extends into the grooves 11 and 30 is guided thereby and by the grooves 16 and 21 when the panel is raised. The ends of the bars 32 and 33 and the slats 37 and 38 are slightly chamfered at their ends adjacent to the sheet 35, so that the panel may fit and 35 take the grooves 10. The bar 33 is provided with a strip 39 at its lower edge, which is long enough to engage the walls of the grooves 11, and between the sheet 35 and strip 11 are sash-locks 40, which may be of 40 any suitable construction. The bar 32 is provided with handholds 41 on its inner surface and with plates 42, which are adapted to engage the walls of the grooves 11. The upper surface of the bar 32 is provided with a 45 tongue 43.

The lower sash 12 is of ordinary construction and comprises the frame 44 and glass 45, which is held in place by strips 46. Plates 47 with trunnions 48 are sunk into the upper 50 edges of the sides of the frame, and movable trunnions 49, operated by locks 50, are situated in lower edges of the sides. The trunnions 49 may be moved by the locks 50 out of the perforations 30, but not out of the 55 grooves in the frame 15 when the sash is in use. The lower end of this sash is provided with a groove which is adapted to engage the tongue 43. Attached to the locks 50 are handholds 51. For convenience the handle 60 50^a of the lock 50 is placed adjacent to the

handhold 51, and this handle 50^a is pivoted at 50^b to a pin in the casing 50^c. A tooth 50^d, attached to this handle, engages a projection 50^e on a dog 50^f, pivoted at 50^g and provided with a lug 50^h, which engages a collar 49^a on the bolt 49 and moves it against the action of a spring 49^b, which rests between said collar and a lug 50ⁱ on the casing when the handle 50^a is depressed. When the handles 50^a are depressed, the sash may be raised or lowered, and the relative positions of the handles 50 and handholds 51 facilitate this operation. The frame 44 is properly mortised to receive the bolt 49, and the casing 50^c is secured by 75 screws 50^m or in any other desired manner. 80

Springs 60 are secured to the upper and inner sides of the frame 44. These springs 60 each comprise a shank 61 with perforations 62, through which screws are passed to secure the spring to the sash, and the shank 61 is integral with a leaf-spring 63, the ends of which are united by a second and oppositely-curved leaf-spring 64. The springs 63 and 64 are both integral, being stamped out of the same piece of metal, and they are separated by a 90 slit and oppositely bent, as above described. Taken together with the integral shank they form the spring 60, which rests against the inner wall of the groove 10 when the sash is in the position shown in Fig. 1 and against 95 the flange 27 when in the position shown in Fig. 2. At all times the springs 60 hold the sash 12 firm and prevent it from rattling or making any movement when the car is in motion. As the leaves 63 and 64 are on opposite sides of the dividing-slit the spring may be compressed until perfectly flat without injury, so that it may occupy a minimum space in the groove 10. This effect is further increased by having the leaf 64 extend beyond 100 the outer edge of the frame 44. 105

The upper sash 13, which is separate and distinct from the lower sash and may be of any suitable size relative thereto, although it is preferably made, as indicated, with a frame 110 52, a glass 53, and strips 54 to secure glass in place. This sash has plates 55 at its upper edges which are sunk flush with the surface and provided with trunnions 56. These plates 55 are provided with curved edges 55^a, which extend beyond the inner sides of the frame 52, and near their upper ends these plates 55 have integral lugs 55^b, which rest on the upper edge of the frame 52 and assist in holding the plates 115 in position. At their upper ends the plates 55 are bent inwardly and downwardly to form hooks 57, which are adapted to engage the trunnions 49 when the sash 12 is raised, so that after this engagement the sashes 12 and 120 13 will be raised together and the curved edges 55^a will engage the plates 47 to more firmly 125 secure the ends 13 to the sash 12.

Each of the upper and lower sashes are identical with those above described.

When the parts of the car are assembled 130

and put together, as indicated in Fig. 1, the sashes 12 and 13 rest, with their trunnions, in the groove 23, and the trunnions 56 on the sash 13 rest in the pockets 24, so that the sash 5 is vertically below in the grooves 31, and the sashes 12 and 13 overlap at their upper and lower edges, respectively, so that the outer edge of the former rests against the inner edge of the latter. The sash 12 rests on the 10 panel 14.

From the foregoing the operation and advantages of my improvement will be readily understood. Assuming the parts to be in the 15 positions indicated in Fig. 1, when the car is adapted to be used as a winter car it is changed to the open condition by withdrawing the trunnions 49 from the sockets or perforations 30 and raising the sashes 12 until the trunnions 48 engage the hooks 57, when both 20 sashes will be raised together and the trunnions will guide them in the groove 23 because of its peculiar shape until the sash 12 rests on the flange 27 and the trunnions 48 have reached the ends of the grooves 23, when 25 the movable trunnions 49 may slide into the upper sockets 30 and secure both sashes in their most elevated positions, where they will be completely concealed beneath the roof of the car by the panel 6. The catches 40 are 30 then released and the panel 14 is raised and guided by the grooves 11, 16, and 21 until it is concealed by the panel 6, when it is secured in place by the catches 40. These steps are repeated until all panel and sashes are raised, 35 when the car will be changed from a closed to an open condition. To change the car from an open to a closed condition, the steps are reversed by first releasing and lowering the panels 14. Then the sashes are released and 40 lowered together until the trunnions 56 on the upper sashes engage the walls of the pockets 25, when the hooks 57 release the trunnions 48, leaving the sash 13 snug in the grooves 31, and the lower sash is lowered until it occupies the position shown in Fig. 1.

It is obvious that by increasing the number of perforations 30 the lower sash may be raised and the window opened any desired distance while the car is in its closed condition.

From the foregoing it is apparent that the 50 improvements therein described enable the sashes to overlap the entire length of the smaller and that one rests on the other in the top of the open car. This structure economizes so much space, as is apparent from Fig. 2, that the sashes may be made much larger and yet be entirely concealed between the roof 5 and the panel 6. As a result the guide-grooves 23 may be considerably shorter than 55 in any other structure heretofore made, and the openings between stanchions may be made as large as desired, a result not obtained with the same ease and efficiency in any other structure.

60 While I have shown and described one em-

bodiment of my invention, it is obvious that many others may be made which are equivalent structures.

Having described my invention, what I claim is—

1. In a convertible car or similar vehicle, stanchions, guides in said stanchions, a panel whose movement is determined by said guides, a sash whose movement is partially determined by said guides, and a second sash which 75 engages the first sash and moves with it after and not before the first sash has reached a predetermined point.

2. In a convertible car or similar vehicle, 80 stanchions, guides with irregular sides forming pockets, upper and lower sashes sliding between said stanchions, the upper sash having one pair of trunnions adapted to engage the walls of said pockets and the lower sash being provided with a plurality of trunnions 85 which engage said guides.

3. In a convertible car or similar vehicle, 90 stanchions, guides with irregular walls forming pockets above grooves in said stanchions, upper and lower sashes, trunnions on said upper sash which rests in said pockets when the sash rests in said grooves, and trunnions on the lower sash engaging said guides.

4. In a convertible car or similar vehicle, 95 stanchions, guides in said stanchions with irregular walls forming pockets above grooves in said stanchions, upper and lower sashes engaging said guides and stanchions so that the upper sash is adapted to slide at one side of the lower sash.

5. In a convertible car or similar vehicle, 100 stanchions, a movable panel, upper and lower sashes sliding between said stanchions and provided with overlapping edges.

6. In a convertible car or similar vehicle, 105 stanchions, overlapping sashes sliding between said stanchions, curved guides on said stanchions, and trunnions on said sashes engaging said guides.

7. In a convertible car or similar vehicle, 110 stanchions, overlapping sashes sliding between said stanchions, guides forming grooves, one groove on each of said stanchions, and trunnions on said sashes engaging said guides.

8. In a convertible car or similar vehicle, 115 stanchions, overlapping sashes sliding between said stanchions, guides in said stanchions and a panel whose movement is determined by said guides.

9. In a convertible car or similar vehicle, 120 stanchions with guides formed therein, upper and lower overlapping sashes adapted to slide between said guides, trunnions on said sashes, and hooks on said upper sash adapted to engage trunnions on the lower.

10. In a convertible car or similar vehicle, 125 stanchions with guides forming grooves, one on each side of each of said stanchions, irregular walls in said guides forming pockets and enlargements in the grooves above the pock-

- ets, and sashes and panels guided by said grooves.
11. In a convertible car or similar vehicle, stanchions with guides, upper and lower overlapping sashes whose movement is determined by said guides, hooks secured to said upper sash, so as to be flush with the edges of its sides, and trunnions secured to plates sunk below the edges of said lower sash so that the 10 said trunnions may be engaged by said hooks.
12. In a convertible car or similar vehicle, stanchions with guide-frames secured therein, flanges secured to the said frames adjacent to their upper ends, overlapping sashes guided by said flanges at the upward limit of their movement.
13. In a convertible car or similar vehicle, stanchions with guide-frames secured therewith, irregular walls in said frames forming 15 pockets and enlarged grooves and panels and sashes whose movement is determined by said frames.
14. In a convertible car or similar vehicle, stanchions with guide-frames secured therein, 20 each of said frames comprising grooved lower portions and a bifurcated upper portion forming two upper arms, one of said arms being grooved to form a continuation of the groove in the lower portion, overlapping sashes adapted to slide in said grooves, fixed panels connecting said stanchions, and a movable panel whose movement is determined by said frames and fixed panels.
15. As an article of manufacture, a guide-frame for convertible cars and the like comprising a grooved lower portion and a bifurcated upper portion forming arms, one of said arms being adapted to act as a guide for a panel and the other being grooved to form a 25 continuation of the groove in the lower portion and an irregular wall on one side of the groove in the upper portion whereby a pocket and enlarged groove are formed.
16. As an article of manufacture, a stanchion which is grooved with adjoining grooves of different depths, a guide-frame with an irregular wall forming a pocket, secured to said stanchion so that said pocket is adjacent to a groove which runs parallel to the lower portion of said frame and is flush with the outer 30 surface thereof.
17. In a convertible car or similar vehicle, stanchions with guiding grooves, sashes adapted to slide between said grooves, and springs 35 with oppositely-curved leaves extending from the edges of said sashes.
18. In a convertible car or similar vehicle, grooved stanchions, sashes adapted to slide between said stanchions, springs with oppositely-curved members secured to said sashes, so that one member of each of said springs extends beyond an edge of the sash.
19. In a convertible car or similar vehicle, stanchions with guides, sashes adapted to slide 40 between said stanchions and whose movement is determined by said guides, and springs with oppositely-curved leaves secured to said sashes by means of a shank.
20. In a convertible car or similar vehicle, stanchions, and sashes, adapted to slide between said stanchions, springs with oppositely-curved leaves connected to said sashes by means of integral shank.
21. In a convertible car or similar device, stanchions, a pair of sashes sliding between adjacent stanchions, springs secured to one of said pairs of sashes, and hooks secured to the other sash of each of said pairs.
22. In a convertible car or similar vehicle, stanchions, pairs of sashes adapted to slide between adjacent stanchions, one of each of said pairs of sashes being provided with springs, and the other sash of each of said pairs being provided with plates with integral hooks.
23. In a convertible car or similar vehicle, stanchions, pairs of sashes adapted to slide between adjacent stanchions, one sash of each pair being provided with springs extending beyond the edge of said sash, and the other sash of each pair being provided with hooks.
24. In a convertible car or similar vehicle, stanchions, pairs of sashes sliding between adjacent stanchions, springs extending from one sash of each pair, plates with integral hooks secured to the other sash of each of said pairs, and projecting edges on each of said plates.
25. In a convertible car or similar vehicle, stanchions, pairs of sashes adapted to slide between adjacent stanchions, springs extending beyond the edges of one of each pair, and plates with projecting edges and hooks secured to the other sash of each pair.
26. As an article of manufacture, a plate for sashes and the like, provided with a hook, and a projecting lug.
27. As an article of manufacture, a plate for sashes and the like, provided with a curved projecting edge, and an integral lug which is adapted to rest on the upper edge of a sash.
28. As an article of manufacture, a sash, a plate secured to said sash, and a projecting lug extending from said plate and resting on the upper edge of said sash.
29. As an article of manufacture, a sash, a plate, with a hook secured to said sash, said plate being provided with a curved and projecting edge.
30. As an article of manufacture, a sash, with a plate secured thereto, an integral hook extending from said plate, and curved edge also extending from said plate, and a projecting lug attached to said plate, which rests on the upper edge of said sash.
31. As an article of manufacture, a sash, springs secured to said sash adjacent to the edge thereof, and movable trunnions extending from the lower edges of said sashes.
32. As an article of manufacture, a sash,

leaf-springs secured adjacent to the edges of said sash near their upper ends, and movable trunnions secured to said sash adjacent its lower end.

5 33. As an article of manufacture, a sash provided with movable trunnions, at its lower edge, and oppositely-curved springs adjacent to its upper edge.

34. As an article of manufacture, a sash with movable trunnions secured to its lower end, leaf-springs with oppositely-curved members secured adjacent to its upper end so that one leaf extends beyond the edges at each side of said sash.

15 35. In a convertible car or similar vehicle, stanchions, pairs of sashes adapted to slide between the stanchions, one sash of each pair being provided with hooks, and the other sash of each pair being provided with movable 20 trunnions.

36. In a convertible car or similar vehicle, stanchions, pairs of sashes adapted to slide between adjacent stanchions, plates with hooks and projecting edges secured to one of each 25 pair of sashes, and movable trunnions secured to the other of each pair of sashes.

37. In a convertible car or similar vehicle, stanchions, pairs of sashes adapted to slide between adjacent stanchions, plates with hooks 30 and projecting lugs secured to one of each pair of sashes, and movable trunnions secured to the other of each pair of sashes.

38. In a convertible car or similar vehicle, stanchions, pairs of sashes adapted to slide between adjacent stanchions, plates with the 35 hooks, lugs and projecting curved edges secured to one of each of said pairs of sashes, and

movable trunnions secured to the other sash of each pair.

39. In a convertible car or similar vehicle, 40 stanchions, pairs of sashes adapted to slide between adjacent stanchions, hooks secured to one sash of each of said pair and springs and movable trunnions secured to the other sash of each pair.

45

40. In a convertible car or similar vehicle, stanchions with guides formed therein, a plurality of sashes, trunnions extending from the edges of one of said sashes, and a hook extending from the edge of an adjacent sash and 50 adapted to engage one of said trunnions.

41. In a convertible car or similar vehicle, stanchions with guides formed therein, a plurality of sashes adapted to slide between said guides, one of said sashes being provided with 55 trunnions extending from the edge thereof, and a second sash thereof provided with hooks extending from its edges and adapted to engage some of said trunnions.

42. In a convertible car or similar vehicle, 60 stanchions with guides formed therein, upper and lower overlapping sashes adapted to slide between said guides, trunnions extending from the edges of one of said sashes, and hooks extending from the edges of the other of said 65 sashes, and adapted to engage some of said trunnions.

Signed in the city and county of Philadelphia, State of Pennsylvania, this 18th day of August, 1903.

HENRY E. HADDOCK.
